L. W. G. FLYNT,
FUEL CONVERTER FOR INTERNAL COMBUSTION ENGINES,
APPLICATION FILED SEPT. 15, 1920.
1,405,196.

Patented Jan. 31, 1922.

Fig. 1.

UNITED STATES PATENT OFFICE.

LOUIS W. G. FLYNT, OF NEWARK, NEW JERSEY.

FUEL CONVERTER FOR INTERNAL-COMBUSTION ENGINES.

1,405,196.

Specification of Letters Patent. Patented Jan. 31, 1922.

Application filed September 15, 1920. Serial No. 410,423.

To all whom it may concern:

Be it known that I, LOUIS W. G. FLYNT, a subject of the King of England, residing at Newark, in the county of Essex and State 5 of New Jersey, have invented certain new and useful Improvements in Fuel Converters for Internal-Combustion Engines; and I do hereby declare the following to be a full, clear, and exact description of the 10 invention, such as will enable others, skilled in the art to which it appertains to make and use the same.

This invention relates to the art of evaporating liquids and mixing the vapor 15 with a gas. It particularly relates to the evaporation of a liquid hydrocarbon and mingling it with a suitable proportion of air or oxygen for purposes of combustion, and is especially designed for the efficient carbu- 20 ration of air to form charges for internal combustion engines.

One of the objects of my invention is to reduce the viscosity of a liquid hydro-carbon fuel when and at the point where it is 25 brought in contact with a current of air or other supporter of combustion in order that the said current may pulverize the liquid into a finer spray whereby a greater surface may be exposed for evaporation and absorption 30 as vapor in the air.

A further object is to adapt a standard type of carburetor to serve as an instrument for the practice of this invention.

The device may be described as a fuel 35 converter inasmuch as it functions in such manner as to increase the fluidity of a liquid fuel.

The invention consists in a means for concentrating heat upon a small volume of 40 gasoline or other liquid fuel just before and at the time when it is brought in contact with a current of air in order to form there- 45 with a combustible mixture. Although the principle of this invention is susceptible of application in a wide variety of instrumen- 50 talities, I have described and illustrated it as embodied in a standard type of carburetor for use in connection with internal combustion engines.

Figure 1 of the drawing is a vertical section through a carburetor embodying said invention, and Figure 2 is an enlarged section on the line 2--2 of Figure 1.

In said drawing the exhaust manifold of 55 an internal combustion motor designed for

use in a motor vehicle is indicated at 1 and the intake manifold at 2. Coupled to said intake manifold is a carburetor designated generally by the letter C. The member 3 contains the air conduit or mixing chamber 60 4 of said carburetor, controlled by a choker valve 4^a and a throttle valve 4^b, and said member is coupled to the intake manifold at 5 in a customary manner. The carburetor illus- 65 trated is of the type in which the air conduit constitutes a U-shaped trap, from the lowest point of which there depends a stem or extension 6, in which is a duct 7, con- 70 trolled by a needle valve 8, fuel flowing through said duct into the depression 9 within the air conduit whence it is taken up by the current of air flowing therethrough to the manifold 2. A bowl or cup-like body 10 constitutes the usual constant level fuel reservoir. The stem 6 has an annular 75 shoulder 11, and a lower threaded end 12. The bottom of the cup 10 is perforated to receive the threaded end 12, and a specially formed nut 13 is screwed on said threaded end, clamping the cup 10 against the 80 shoulder 11 and the member 3 containing the air conduit and mixing chamber 4 in such manner as to form fluid tight joints. The usual float 14 controls the fuel inlet valve, 85 which admits fuel to the reservoir.

In carburetors of the type shown it is cus- 90 tomary to provide an overflow port or duct 15 in order to prevent accumulation of an ex-cessive amount of fuel at the lowest portion 9 of the trap-like conduit 4, this accumula- 95 tion of fuel resulting from the suction of the engine when starting with the air choke valve 4^a closed, or partially closed, as is customary.

In the embodiment of the invention illus- 95 trated I have substituted for the usual nut which secures the cup 10 in place, the said special nut 13. Said nut 13 has a threaded counterbore 16 engaging the threaded end 12 of the depending member 6, and a smaller 100 bore 16^a communicating with the center of the counterbore. When the special nut 13 is in place, there is a chamber 17 between the end of the threaded portion 12 and the lower inner surface of the counterbore 16 in the 105 nut. Radiating from this chamber 17 are a plurality of lateral ducts 18. Assuming that nut 13 is of hexagonal form, there are preferably six of these radiating ducts.

Connected with the bore 16^a of the nut 13 110

is a small tube 19, the other end of which is tapped into the exhaust manifold 1 at 20.

By means of the construction illustrated and described it will be apparent that when 5 the engine is in operation a small portion of the hot exhaust gases will be by-passed from the exhaust manifold through the tube 19 some of which will pass up through the duct 15 into the air conduit or mixing chamber 10 4 immediately adjacent the needle-valve-controlled fuel inlet. As the hot gas duct 15 lies closely adjacent to the fuel duct 7, the hot gases on their upward passage through duct 15 will heat the fuel in said duct 7. 15 A larger part of the gas flowing in tube 19 will escape through radial passages 18 in the coupling member 13. As the area of the hole through which the hot gas enters the air conduit is small and the distance from 20 the exhaust manifold is relatively great, it is desirable to provide said escape orifices 18 through the nut or coupling member 13 in order that a high temperature may be maintained in the wall surrounding the fuel 25 conduit 7. The radial passages 18 permit free flow of a relatively large volume of hot gas, provide additional surface for absorption of heat by the member 6 within which the fuel duct 7 is formed, an effective 30 means of muffling the sound of the gas escaping from the tube 20 and utilizing its heat without injecting any considerable volume of burnt gas into the mixing chamber.

It is essential to the efficient operation of 35 an internal combustion motor that the oil or gasoline entering the cylinders mixed with air shall be in vapor form; that the charge shall be free from drops of liquid fuel oil suspended in the air and vapor; liquid gasoline 40 line does not burn; in order to be burned it must be vaporized and mixed with air or oxygen. It is therefore important in forming charges for internal combustion engines to completely vaporize the fuel oil that enters 45 the cylinders.

Rapidity of evaporation of a liquid under uniform temperature depends upon the area of exposed surface. The exposed surface of a volume of liquid is increased by subdividing it. For example, a cubic inch of gasoline would expose six square inches of surface, and if said cubic inch were broken up into cubes of one thousandth of an inch each, there would be one thousand million 50 of them, and they would expose a surface of six thousand square inches. Under the same conditions the speed of evaporation of the cubic inch broken into cubes of one thousandth of an inch would be one thousand 55 times faster than the speed of evaporation of the solid cubic inch.

The theory of operation of the pulverizing carburetor is that the air current drawn through the air conduit meets the stream of 60 gasoline entering, commonly transversely of

said current, and breaks the gasoline into small globules, the size of which depends mainly on the viscosity of the gasoline, in order that as large a surface as possible shall be exposed to the air, and that the air 70 may absorb the gasoline and carry it into the cylinders in vapor form. If the viscosity of the gasoline is reduced, as by heating it, the globules in the air current will be smaller, the surface exposed to evaporation correspondingly greater, and the consequent absorption of vapor by the air more complete. 75

It is my intention to heat only that portion of the fuel that is in the passage controlled by the needle valve and close to the discharge point. It is not new nor is it desirable to heat the whole contents of the float chamber, as such a condition would tend to cause losses through premature evaporation.

In the construction shown some heat is 80 radiated and conducted to the contents of the float-controlled reservoir from the center outward but the strong air current from the fan, which is customarily found in the front of internal combustion engines on motor 85 vehicles, will minimize losses from evaporation in the reservoir. It is a matter of common knowledge that carburetors have been designed in which reservoir bowls or cups provided with jackets through which hot 90 water or hot gases are circulated so as to heat a considerable volume of gasoline before it is conducted and discharged into the air current. It is also common knowledge that the current of exterior air drawn in to be saturated with the vapor and serve as a supporter of combustion is heated from outside sources, as from a stove taking heat from the exterior of the exhaust pipe or manifold. In the device herein described it is intended 95 to concentrate heat in a small volume of fuel immediately before discharge into the air stream in order that the viscosity may be reduced to the lowest point, namely that which obtains just before the boiling point 100 is reached. It is the intention to avoid as much as possible heating the gasoline or other fuel in the bowl or maintained reservoir of liquid fuel. 105

The carburetor illustrated is of a type commonly supplied as a portion of the equipment of the Ford motor and may be either of the carburetors marketed as Holley or Kings-ton carburetors.

Having described my invention in a manner to enable those skilled in the art to which it appertains to make and use the same, what I desire to secure by Letters Patent is:

1. In a device of the class described, a 115 member having an air conduit, and adjacent independent fuel and hot gas ducts opening by separate ports into said air conduit; and means whereby said ducts may be placed in communication with the source of fuel 120

and hot gas, respectively, said hot gas duct having a port adapted to discharge outside of said member.

2. In a device of the class described, a member having an air conduit comprising a U-shaped trap, there being a fuel duct discharging into the depressed portion of said trap, and a duct adjacent to said fuel duct opening into said depressed portion, and means for connecting the outer end of said last mentioned duct with a source of hot gas.

3. In a device of the class described, a member having an air conduit comprising a depressed portion, there being a fuel inlet duct discharging into said depressed portion, and a duct adjacent to said fuel duct opening into said depressed portion, means to connect the outer end of said last mentioned duct with a source of hot gas, said last mentioned duct also communicating laterally with the external air.

4. A carburetor of the class described comprising a mixing chamber and a fuel reservoir, a stem passing through said reservoir, said stem having a fuel duct communicating with the reservoir and mixing chamber, and a duct extending through said stem adjacent to said fuel duct, a tube connecting said last mentioned duct with a source of hot gas, there being a lateral passage connecting said duct with the outer air external of said reservoir.

5. In a device of the class described, a carburetor comprising a member including a

U-shaped air conduit communicating with the intake manifold of an engine, a stem depending from the lowest portion of said air conduit, said stem having a threaded lower end, a bowl surrounding said depending stem, said stem having a fuel duct one end of which communicates with the interior of said bowl and the other end with the lowest portion of said air conduit, there being also a duct extending longitudinally through said depending stem adjacent to said fuel duct, a counterbored coupling nut secured on the threaded end of said depending member securing said bowl in place, said coupling nut having ducts radiating from the counterbore, and a tube connecting the bore of said nut with the exhaust manifold of an engine.

6. A coupling member having a chamber formed in one side, passages radiating from said chamber and an axial orifice extending from the bottom of said chamber through the opposite side.

7. A carburetor attachment comprising a coupling member having a bore and counterbore and passages radiating from the counterbore.

8. A carburetor attachment comprising a threaded nut having passages radiating from a threaded opening therein, said nut having an axial orifice communicating with said threaded opening.

In testimony whereof I affix my signature.
LOUIS W. G. FLYNT.
